UNITED STATES PATENT OFFICE.

GEORGE F. SHAVER, OF NEW YORK, N. Y., ASSIGNOR TO BENJAMIN P. WHEELER, OF SAME PLACE.

MECHANICAL-TELEPHONE SWITCH.

SPECIFICATION forming part of Letters Patent No. 365,868, dated July 5, 1887.

Application filed September 20, 1886. Serial No. 213,974. (No model.)

To all whom it may concern:

Be it known that I, GEORGE F. SHAVER, a citizen of the United States, and a resident of New York, in the county of New York and State 5 of New York, have invented certain new and useful Improved Switching Apparatus for Mechanical-Telephone Wires, of which the following is a specification.

The object of my invention is an improved 10 mechanical apparatus or switch, by means of which different mechanical-telephone wires may be connected and made operative with ease and dispatch, as necessary in a central or connecting office. For this purpose I employ the apparatus shown in the accompanying drawings, of which—

Figure 1 is a sectional elevation of my invention. Fig. 2 is a plan view of the same. Fig. 3 is a front view of a detail.

20 The same letters refer to the same parts throughout.

In mechanical telephones when a person in one place desires to communicate with some one at a distance it is necessary to make a 25 connection between the wires leading to the two places which shall make them act as one continuous wire. For this purpose the various wires of a telephone system are all led into a central or switching office, where their 30 terminals are arranged and supported in a convenient position for connecting any two of them at will, giving them the proper tension for use. Thus the various wires are led to a large ring, A, of sufficient strength to bear 35 the necessary tension, and their ends or terminals a are passed through holding-blocks B, mounted in the ring A, and secured by means of collars a'. The ring A consists of two parts separated and connected by means 40 of the guides H incasing the blocks B. These guides H are provided with pintles or sockets h, for supporting the connecting apparatus when in use. The blocks B have a series of elastic wires, b, mounted upon their front surfaces, through the centers of which the line-wires are passed, as shown in Fig. 3. In place of the wires b the block B may be provided with a rubber bushing, b', which is protected from wear by a brass lining, b'', as shown 45 in Fig. 2. The terminal a is provided with a loop or hook, a'', for attaching the connecting-wire.

The connecting apparatus or switch is duplex, consisting of two similar arrangements properly connected and working in conjunction with each other. One description will apply to both. Thus each consists of a tube or guide, C, having the necessary loops c for hooking it onto the pintles h, by which it is supported, and having secured upon its upper surface a straight rack of ratchet form, as shown at c'. The tube C is also provided with a slot, c''. In the tube C is fitted to slide freely a rod, D, which has a lug or projection, d, which passes out through the slot c''. To the lug d is hinged a forked or double lever, E, which passes up both sides of the tube C, and carries two sets of pawls, e, as shown. The pawls e engage the ratchet c', and their arrangement is such that when the lever E is moved one of the pawls e will force the rod D out of the tube C, while the other pawl prevents its returning. The lever E is operated by means of the handle e', and connecting-rods e'' and thumb-keys e''' are provided, by 75 means of which the pawls e may be tripped and the rod slid back into the tube C, when desired. At their outer ends the two rods D of the duplex system are secured together by a link, F, and hinge-joints f, which permit 80 them to assume any angle in relation to each other. To the link F is secured a loop of wire or metal, f', attached to which is the equalizing-bar G. A rubber washer, g, is secured under the head of the attaching-wire g'. To 85 each end of the equalizing-bar G is secured a wire, g'', which is made of the proper length, and provided with a hook or loop, g''', by means of which it is connected to the terminal a of the desired line-wire.

When it is desired to connect any two line-wires, the apparatus is hooked onto the proper pintles, h, the hooks g''' are connected with the terminals a, and the necessary tension given by means of the levers E, making an 95 effective apparatus, which may be readily changed from wire to wire, as the exigencies of the business may require.

Having thus described my invention, what I claim, and desire to secure by Letters Patent, 100 is—

1. In mechanical-telephone switches, the block B, having the cross-wires b, in combination with the terminals a of the line-wires,

and the ring A, substantially as herein shown and described.

2. In mechanical-telephone switches, the guides H, having the pintles h, in combination with the switching apparatus, as herein shown and described.

3. In mechanical-telephone switches, the switching apparatus herein described, consisting of the tubes C, having the loops c, ratchets c', and slots c'', and the rods D, having the lug d, in combination with the levers E, pawls e, connecting-rods e', and thumb-keys e'', and the link F, loop-hinges f, loop f', and equalizing-bar G, having the wire g', rub-

ber washer g, and wires g'', when constructed 15 and operated substantially as and for the purposes herein shown and set forth.

4. In mechanical-telephone switches, the combination of the equalizing-bar G and terminals a of the line-wires, when constructed 20 and operated as herein shown and described.

Signed at New York, in the county of New York and State of New York, this 16th day of September, A. D. 1886.

GEORGE F. SHAVER.
